UNITED STATES PATENT OFFICE.

MELVIN I. BOWEN, OF HARLAN, KENTUCKY.

RAIL-CLAMP.

1,253,133.

Specification of Letters Patent.

Patented Jan. 8, 1918.

Application filed May 15, 1917. Serial No. 168,875.

To all whom it may concern:

Be it known that I, MELVIN I. BOWEN, a citizen of the United States, residing at Harlan, in the county of Harlan, and State of Kentucky, have invented new and useful Improvements in Rail-Clamps, of which the following is a specification.

This invention relates to rail clamps and aims to provide means for clamping sections 10 of track together for the temporary extension thereof.

The object of the present invention is to provide means whereby sections of track may be securely clamped together to form 15 joints for temporary track extensions, without the necessity of drilling holes in the rail ends and fishing plates, the invention being susceptible of repeated use, so that its cost is reduced to the minimum.

Another object of the invention is to provide a clamp which may be utilized to hold 20 a guard rail upon either a temporary or a permanent track, the invention being capable of use with either the ordinary wooden tie or with ties constructed of metal or other material.

Another object is to provide a joint or tie which is of simple and cheap construction, the nature of the joint rendering it possible 25 to utilize an old section of rail as the connecting bar, the whole being simple and quickly adjusted to connect the rail ends and when desired may be quickly disconnected for further use.

With these and other objects in view, the invention consists of the following novel combination and arrangement of parts, hereinafter more fully described, illustrated in the accompanying drawings and pointed out 30 in the appended claims.

In the drawings:

Figure 1 is a perspective view of a temporary rail joint embodying the present invention;

Fig. 2 is a transverse, sectional view through the rail with the joint in position;

Fig. 3 is a detailed perspective view of the adjustable clamping jaw;

Fig. 4 is a transverse sectional view illustrating the use of the invention with a metal tie; and

Fig. 5 is a similar view of a further modification of the invention.

Referring in detail to the drawings, the improved rail joint is shown as connecting

the meeting ends of the rail sections R, one of said sections representing the end of a permanent track and the other section representing the end of a temporary track. Secured transversely of the rails R, are clamping bars 10, there being preferably provided one of these bars for each rail section. The bars 10 extend beneath the base flange of the rails and are provided with extensions 11, the faces 12 of which are adapted to fit the fishing spaces of the rails. The extensions 11 are further provided with lower inclined faces 13 which rest upon the upper inclined portion of the rail flanges and by this means the bar 10 is connected to the rails. The 70 clamping bars extend for some distance beyond the sides of the rails to provide supporting means for the adjustable clamping jaw, 14, which is provided with an opening 15 to receive the bar 10 and provide for the 75 adjustment of the jaw upon the bar. Any suitable connecting means may be interposed between the inner faces 16 of the jaws 14 and the rails R, but it is preferred to utilize a short section 17 of a rail, as these sections 80 are usually available in laying temporary tracks. The rail section as shown provides a straight surface 19 for engagement with the inner face 16 of the adjustable clamping jaw. In addition to providing a convex face 85 18 for contact with the web of the rail, the head of the section 17 lies within the fishing space beneath the heads of the rail ends R and their flanges so as to prevent vertical displacement of the said ends. In order to quickly adjust and secure the section 17 in position, the clamping bar is provided with a transverse slot 20, which is adapted to receive a wedge 21, which, when driven within the slot will force the rail section 90 17 tightly against the rail ends R and securely hold them against lateral movement. If desired the wedge 21 may be secured to the clamping bar by means of a chain 22, so that it will always be at hand for convenient use.

As shown in Fig. 4 of the drawings, the invention is susceptible of use in connection with a metal tie and in addition to providing means for connecting the adjacent ends of 105 the rail sections together for track extension purposes, the invention is also susceptible of use as a guard rail in connection with either a temporary or a permanent track, the connecting rail section being so 110

positioned as to receive the flange of the rail, after the manner of the usual guard rail.

In the construction shown in Fig. 4, 23 5 represents a fragmentary section of a suitable form of metal tie construction, for example, the Carnegie or the Slick steel tie. This tie has secured thereto as shown at 25 10 the base flange of the rail R for the purpose of preventing movement of the rail in that direction. The rail section 27 which is utilized for the purpose of connecting the adjacent rail ends or for providing the guard 15 rail, is positioned after the manner of the sections shown in Figs. 1 and 2, that is with the head thereof located within the fishing spaces of the adjacent rail ends and in contact with the web thereof. The base flange 20 of the section 27 has positioned thereagainst a clamping member 28, which consists of a substantially vertical member 29, and a horizontal member 30, the said horizontal member being pivoted or otherwise secured to 25 the tie 23 as shown at 31. The extremity of the member 30 is formed into an engaging hook 32, which is adapted to engage a groove or depression 33 formed in the top face of the tie. The clamping block 34 is 30 positioned beneath the rail section 27 and has its upper face engaged with the lower or under fishing space of the rail section 27 to provide a support therefor. The block 34 is formed with a recess 35, which is 35 adapted to receive the flange of the rail section R to aid in securing the said rail section in position. It will be seen that from the foregoing the block 34 provides an effectual support for the connecting rail 40 section 27, so as to securely hold the same in position to enable the head thereof to be wedged beneath the head of the rail section R and in addition to performing this function serves as a clamp for the said rail section R.

In the modification shown in Fig. 5, the hook 32 and depression 33 are dispensed with, the clamping member 36 being held to the tie by means of a pin 37, which is upset 50 or riveted beneath the tie as shown. In this form, the block 38 is secured to the tie in the same manner as the clamping member 36, as shown at 39, the said block being further extended upon the base flange of the 55 rail R as shown at 40 so as to extend partially beneath the head of the connecting rail 27.

It is thought that from the foregoing de-

scription when taken in connection with the accompanying drawings, the uses and advantages of the invention will be apparent and that a further description is unnecessary.

Having described the invention, what is claimed is:

1. A rail clamp comprising transversely arranged clamping bars detachably engaged with the rail ends, vertically arranged clamping jaws adjustably mounted upon said bars, a rail section interposed between the inner faces 70 of the clamps and the web of the rails, said section bridging the point between said rail ends and wedges adapted to be inserted within slots formed in the clamping bars and engageable with the clamping jaws. 75

2. A rail clamp comprising a rail section adapted to have its head positioned within the fishing spaces of adjacent rail ends and its tread portion engaging the webs thereof, means for holding said adjacent rail ends against movement in a direction away from said rail section and means engageable with the base flange of the rail sections for holding the same against movement. 80

3. A rail clamp comprising a rail section adapted to have its head positioned within the fishing spaces of adjacent rail ends and its tread portion engaging the webs thereof, means for holding said adjacent rail ends against movement in a direction away from said rail section and adjustable means engageable with the base flange of the rail section for holding the same against movement. 85

4. A rail clamp comprising a transversely arranged member detachably engaged with the rails, a vertically arranged clamping element carried thereby, a rail connecting member interposed between the inner face 100 of the clamping element and the webs of the rails and a supporting block interposed between the transversely arranged member and the rail connecting member.

5. A rail clamp comprising a transversely arranged member detachably engaged with the rail, a vertically arranged clamping element carried thereby, a rail connecting member interposed between the inner face of the clamping element and the webs of the rails 110 and a supporting block interposed between the transversely arranged member and the rail connecting member and engaged with the flanges of the rails.

In testimony whereof I affix my signature. 115
MELVIN I. BOVEN.
